UNITED STATES PATENT OFFICE

2,527,033

RATCHET WRENCH

Robert H. Rodgers, Arlington, and Alvah B. McKinney, Fort Worth, Tex.

Application December 10, 1947, Serial No. 790,732

1 Claim. (Cl. 81—61)

1

This invention relates to hand tools and has reference to a ratchet wrench.

An object of the invention is to provide a ratchet wrench having an opened end and adapted to use on the unions of hydraulic lines close to walls where an ordinary opened end wrench cannot conveniently be used.

Another object of the invention, in addition to the foregoing, is to provide a wrench of the referred to class wherein the wrench heads are interchangeable so as to accommodate various sizes of unions, nuts, and bolt heads.

A further object of the invention is to provide a ratchet wrench having a rotatable head, and which head has sufficient bearing surface to apply adequate force to the same when turning an object having wrench surfaces.

A further object of the invention is to provide a ratchet wrench having an extendable jaw for rotatably securing a wrench head, and wherein there is little or no shearing force applied to the pivot pin of the jaw.

These and other objects of the invention will become apparent from the following description of the accompanying drawing, wherein:

Figure 1 is a side elevational view, partly shown in broken section, of a wrench embodying the features of the present invention.

Figure 2 is a bottom view of the wrench illustrated in Figure 1.

Figure 3 is a view similar to Figure 1, but showing the jaws of the wrench in their opened position and with the wrench head removed.

Figure 4 is a side elevational view of a wrench head forming part of the present invention, and

Figure 5 is an end view of Figure 4.

The illustrated form of the invention includes a tubular handle 1 having a housing 2 integral therewith. The housing 2 is relatively flat and has a recess 3 which is open in one side of the housing to receive the arm 4 of a jaw 5. The end of the housing 2 is extended to form a coacting jaw 6 which is opposingly arranged with respect to the first referred to jaw 5. The arm 4 is substantially circular at its inner end where the housing 2 is recessed to rotatably receive the same. A pivot pin 7 extends through the housing 2 and the diametric center of the end of the jaw arm 4, and the edge of the housing adjacent the jaw 5 is arcuate to accommodate a step 8 formed between the jaw 5 and the jaw arm 4. The opposing surfaces of the jaws 5 and 6 are also arcuate to receive the annular bearing surfaces 9 of a substantially circular wrench head 10.

The wrench head 10 includes an opening 11 in

its side to receive opposing wrench surfaces of a nut, union, or the like, and as particularly shown in Figures 1 and 4, the opening is of sufficient depth to place the nut acted upon at the center of the wrench head. Teeth 12 having the same angle on each side are provided between the bearing surfaces 9 of the head 10, and, as will be seen, lend toward making the tool foolproof. The jaws 5 and 6 of the wrench are arcuately recessed, as at 13 and 14, to accommodate the teeth 12 of the head 10.

Within the movable jaw 5, and extending into the recess 13 there is a pawl 15 secured in place by a pawl pin 16. The pawl 15 is located in a recess 17 in the jaw 5 and is arranged to engage the teeth 12 of the head 10. For this purpose a small spring 18 is located in the pawl recess 17 for normally maintaining the length of the pawl at a right angle with respect to the angle of any tooth 12 it engages. Similarly, another pawl 19 is located in a recess 20 within the housing 2, and the end of the pawl extends into the stationary jaw recess 14 to engage any of the teeth 12 at a right angle. The second referred to pawl 19 is also actuated by means of a spring 21 in the pawl recess 20. The reason for the separate pawls 15 and 19 is to accommodate the width of the wrench slot 11 when there are no teeth to act upon, as occasioned when the slot is turned inwardly.

There is a shoulder 22 on the jaw arm 4 at a location in line with the axial center of the tubular handle 1, the purpose of which is to actuate the jaw 5 when acted upon by a pin 23 extending through the handle. The pin 23 is enlarged near its outer end and has threads 24 thereon to threadedly engage the inside diameter of the handle 1. Integral with the threaded portion 24 of the pin 23, and outwardly of the handle 1, there is a knurled knob 25 for manually moving the pin 23 for closing the movable jaw 5. A small spring 26 is positioned between the body of the housing 2 and the jaw arm 4 for opening the jaw 5 when the pin 23 is moved outwardly.

In operation, heads 10 having various sized openings 11 may be engaged between the jaws 5 and 6 by turning the knob 25. The opening 11, when assembled as described, is applied to a union, nut, or bolt head, or the like, to be turned. Thus, by operating the handle 1 the part to be threadedly secured or disengaged is turned as far as necessary. By reason of the described construction and arrangement there is little or no shear on the pivot pin 7, and there is sufficient bearing surface, as at 9, to prevent binding of the head 10. While the pawls 15 and 19 are set

for imparting a given direction of rotation to the head 10, the direction of rotation applied to the nut or bolt may be reversed by removing the wrench assembly and head 10 therefrom and turning the assembly so as to cause the said head to turn in an opposite direction when the handle 1 is operated.

The form of the invention described is not restrictive but may be made in many ways within the scope of the appended claim.

What is claimed is:

A ratchet wrench comprising a handle, a stationary arcuate jaw secured to one end of said handle, and a hinged arcuate jaw pivotally secured relative to said end of said handle, a substantially circular wrench head adapted to be received within the arcs of said jaws and rotated therein, a slot in said wrench head, teeth having substantially equal angles relative to their respective radii around the periphery of said head, a pawl pivotally secured to said stationary jaw and arranged to perpendicularly contact the side of the tooth acted upon, and a second pawl carried by said pivoted jaw and also arranged to

perpendicularly contact the side of the tooth acted upon, and threaded means extending through said handle and contacting said hinged jaw for actuating the latter relative to the first said jaw.
